CLAIM

The ornamental design for a meat wrapped pet treat, as shown and described.

DESCRIPTION

FIG. 1 is a perspective view of a first embodiment of a meat wrapped pet treat;

FIG. 2 is a left side elevation view thereof;

FIG. 3 is a right side elevation view thereof;

FIG. 4 is a front elevation view thereof;

FIG. 5 is a back elevation view thereof;

FIG. 6 is a top plan view thereof;

FIG. 7 is a bottom plan view thereof;

FIG. 8 is a perspective view of a second embodiment of a meat wrapped pet treat;

FIG. 9 is a left side elevation view thereof;

FIG. 10 is a right side elevation view thereof;

FIG. 11 is a front elevation view thereof;

FIG. 12 is a back elevation view thereof;

FIG. 13 is a top plan view thereof; and,

FIG. 14 is a bottom plan view thereof.

The stippled shading and the other portions of the design that are not shown with stippled shading represent a contrasting appearance. The break lines shown in the middle portion of the meat wrapped pet treat in FIGS. 8-10, 13 and 14 indicate that the appearance of any portion of the article between the break lines forms no part of the claimed design.
